(57) **CLAIM**

The ornamental design for a display screen with software application graphical user interface window, as shown and described.

DESCRIPTION

The single FIGURE is a front view of a software application user interface window for a display screen our new, original and ornamental design.

The outermost broken line illustrates the display screen and the remainder of the broken lines illustrate portions of the software application graphical user interface window. None of the broken lines form part of the claimed design.

1 Claim, 1 Drawing Sheet
